Patented Aug. 5, 1919.

UNITED STATES PATENT OFFICE.

SAMUEL R. KITCHEN, OF BUFFALO, NEW YORK.

SPRING-MATTRESS AND THE LIKE.

1,312,125.

Specification of Letters Patent. Patented Aug. 5, 1919.

Application filed February 25, 1918. Serial No. 219,000.

To all whom it may concern:

Be it known that I, SAMUEL REUBEN KITCHEN, of the city of Buffalo, in the State of New York, United States of America, 5 have invented certain new and useful Improvements in Spring-Mattresses and the like, of which the following is a specification.

This invention relates to resiliently supported and flexible fabrics commonly employed in spring mattresses, spring seats and the like, and my object is to devise resilient supporting means for such fabrics which will reduce to a minimum the sagging 15 in the middle, which is the common fault in such structures, while providing ample resiliency for comfort.

I attain my object by forming the mattress of a flexible, inelastic metal fabric and by 20 supporting it along two or more edges from rock arms resiliently connected to the mattress frame and normally extending diagonally upward from the frame toward the opposite side thereof, so that weight supported on the mattress fabric tends to swing 25 the arms down toward, or below, the horizontal, substantially as hereinafter more specifically described and as illustrated in the accompanying drawings in which—

30 Figure 1 is a plan view of a spring mattress constructed in accordance with my invention;

Fig. 2 a longitudinal section of the same, partly broken away; and

35 Fig. 3 a front elevation showing one of the springs connected to the mattress frame and the flexible fabric of the mattress.

In the drawings like numerals of reference indicate corresponding parts in the different 40 figures.

1 is a mattress frame made of metal angle bars the external angle of each being at the upper outer side as indicated more particularly in Figs. 2 and 3. 2 is a flexible, substantially inelastic, mattress fabric of any ordinary type. I illustrate a wire net work connected to stout side wires 3. The fabric is connected to and supported by a plurality of rock arms 4 resiliently connected to opposite 45 sides of the mattress frame and to the mattress fabric. These rock arms normally extend diagonally upward from the frame toward the opposite side thereof as shown more particularly in Fig. 2. The result of 50 this construction is that the mattress fabric is normally held stretched at a higher level

than the mattress frame so that when the mattress is depressed by the placing of any weight thereon, the arms will swing downward as shown in dotted lines in Fig. 2 without any material increase of the distance between their ends, so that the depression of the mattress fabric produces a minimum of sag therein.

While any form of rock arm might be 65 employed, I show a preferred construction in which the rock arm is formed of spring wire doubled up on itself to form the rock arm and having the ends formed with coils 5 through which passes a cross bar 6, preferably a metal tube, which is secured in the angle of the frame member by means of bolts 7. The ends 8 of the coils being held between the angle bar frame and the cross bar, the coils cannot turn, and thus they 70 form springs tending to hold the rock arms in the upwardly inclined position shown. The rock arms, it will be noted, lie substantially flat against the underside of the horizontal legs of the angle bar frame member 80 and then bend to extend inwardly and upwardly. The coils 5 being in tension the rock arms have their normal positions strictly defined and side sway is minimized. The ends of the rock arms are preferably 85 formed with turned down hooks 9 adapted to engage the mattress fabric. These hooks cannot disengage as the upward swing of the rock arms is strictly limited by the frame.

For most purposes, it is sufficient to employ these rock arms at the ends only of the mattress frame, but they may also be employed at each side as shown in Fig. 1 to 90 assist in preventing sag at the center of the mattress fabric.

The number employed at the ends will necessarily depend on the width of the mattress frame and the strength of the spring material used in the arms and coils.

The invention is equally as applicable to 100 spring seats of all kinds as to mattresses and will also prove of great value for use in the construction of stretchers for carrying the wounded or sick in connection with military or civil hospitals, as the absence of 105 center sag in the mattress adds materially to the comfort and therefore to the well being of the patient.

What I claim as my invention is:—

In spring mattresses and the like, the 110 combination of a frame, opposite sides of which are formed by angle bars with their

external angles forming the outer upper edges of the sides; cross bars secured to the inner angles of said angle bars; rock arms having coils formed thereon through which the cross bars pass, the ends of each coil being straight and engaging the inner surface of the downwardly directed leg of the angle bar; said arms normally substantially en-

gaging the upper leg of the angle bar and then extending diagonally upward from the angle bar toward the opposite side of the frame; and a flexible substantially inelastic mattress fabric connected at its edges to said rock arms.

SAMUEL R. KITCHEN.
